UNITED STATES PATENT OFFICE.

HORATIO G. GILLMOR, OF WASHINGTON, DISTRICT OF COLUMBIA.

RAIL-ANCHOR.

1,251,012.

Specification of Letters Patent. Patented Dec. 25, 1917.

Application filed June 18, 1915. Serial No. 34,820.

To all whom it may concern:

Be it known that I, HORATIO G. GILLMOR, a citizen of the United States, residing at Washington, in the District of Columbia, have invented a new and useful Improvement in Rail-Anchors, of which the following is a specification, accompanied by drawings.

This invention relates to devices known as rail anchors, rail stays or anticreepers and one of its objects is to form a simple device which will prevent the longitudinal movement of the rails of rail stays.

Other objects of the invention are to provide for locking the device upon the rail in such a manner as to prevent the accidental loosening or detachment of the device and to provide a device which may be constructed in one piece.

20 In the accompanying drawings, in which one embodiment of the invention is illustrated:

Figures 1, 2 and 3 are, respectively, a plan view, a side elevation and a sectional elevation of the device in operative position on the rail. Figs. 4 and 5 are, respectively, a sectional elevation and a plan view illustrating the manner of applying the device to the rail and Fig. 6 is a perspective view 30 of the rail anchor detached from the rail.

Similar letters refer to similar parts throughout the several views.

A represents the rail, B the cross tie and C the rail anchor. The body of the anchor 25 C is transverse to the rail and, on one end is formed a portion D, extending above the rail base, having a face or shoulder E arranged to engage the edge of the rail base and an arm G turned at an angle to the body 40 of the anchor C and arranged to engage the upper surface of the rail base so that the rail base is gripped between the arm G and the body of the anchor C. At the other end of the body of the anchor C there is a portion H extending above the bottom of the rail and provided with a face or shoulder I arranged to engage the edge of the rail base 45 opposite to the shoulder E. This end of the anchor C is turned downward and forward at F and upward at L to form a portion M, the upper portion of which extends above the rail base and is provided with a face or shoulder N and an arm O turned back toward the body of the anchor C and arranged 50 to engage the top of the rail base flange.

The device is placed in position on the rail by placing the body of the anchor C below and at an angle to the rail with the arm O of the portion M engaging the upper surface of the base flange of the rail and the shoulder N engaging the edge of the rail base as illustrated in Fig. 5. In this position the end of the arm G will just clear the edge of the rail base and the body of the anchor C may be raised until the arm G will be ready to engage the upper surface of the rail base flange at the side of the rail opposite to shoulder N, as illustrated in the sectional view Fig. 4. The two arms G and O may thus be brought to engage the upper surfaces of the rail base flange at opposite sides of the rail; and, in this position, the shoulder I will be below the rail bottom, as illustrated in Fig. 4, and the engagement of the portion M with the bottom of the rail base and the arm O with the top of the rail base will through parts L, K and F, be forcing the portion H of the body of the anchor C upwardly against the rail bottom. By moving the anchor C angularly on the rail with the shoulder N in engagement with the edge of the rail base the arm G will be brought to engage with the upper surface of the rail base and the portion H of the other end of the body of the anchor C will approach the edge of the rail base. When the position illustrated in Fig. 1 is reached the upward pressure of portion H upon the bottom of the rail will cause this end of the body of the anchor C to spring up and bring the shoulder of face H into engagement with the edge of the rail base. In this position of the device the rail base edges at opposite sides of the rail are engaged by the faces or shoulders E and I and one side of the rail base is gripped between the body of the anchor C and the arm G. The rail base, at the other side of the rail is gripped between the portion M and its arm O and there is some pressure exerted by the body of the anchor C upward upon the rail bottom.

When first applied to the rail the portion M of the anchor C will generally not be in contact with the cross tie B. The direction in which the rail tends to move is indicated by the arrow in Fig. 2 and this direction will be referred to as forward. The first effect of the forward movement of the rail is to carry with it the anchor until the portion M comes into contact with the cross

tie, as illustrated in Figs. 1 and 2. After this position is reached any further tendency to forward movement of the rail causes pressure to be exerted by portion M upon 5 the cross tie and by the cross tie upon portion M and this pressure tends to cause portion M to cant very slightly and, therefore, presses the body of the anchor C upward against the rail bottom. Moreover, since the 10 rail base is gripped at one side between arm G and the body of the anchor C a forward movement of the rail will carry with it this end of the anchor C and cause the anchor C to move angularly or skew slightly 15 on the rail. This angular movement or skewing will cause the rail base to be gripped between the faces or shoulders E and I and a relatively small movement of the rail will be sufficient to so increase the 20 grip of the anchor C upon the rail as to resist all tendency to further forward movement.

If, for any reason, the rail moves in the backward direction it will carry the anchor 25 C with it and the portion M will be carried out of contact with the cross tie B. This movement will however not affect the grip 30 of the device upon the rail and the engagement of the opposite edges of the rail base by the shoulders E and I. It will readily be understood that the device cannot be accidentally loosened or rendered inoperative.

It will also be obvious that the device may be readily and cheaply fashioned from a 35 sheet or plate of steel which may be cut to a desired form and then pressed or otherwise shaped.

While I have described my invention as embodied in one form, modifications might 40 be made without departure from the principles of the invention. Therefore, I do not wish to be understood as limiting the invention to the particular construction and arrangement shown and described except so 45 far as these limitations are specifically set forth in certain of the claims herein.

I claim and desire to secure by Letters Patent:—

1. An anticreeper, comprising a cross bar 50 recessed to receive the rail base flange and engage the opposite edges thereof held in engagement with said rail base by an arm engaging the upper surface of the rail base at one side of the rail and by an upward 55 pressure exerted upon said bar at the other side of the rail by a rail base and tie engaging element in tending to assume a position from which said element was sprung.

2. An anticreeper, comprising a cross bar 60 having at one end rail base edge and upper surface engaging means and at the other end a shoulder held in engagement with the rail base edge by an upward pressure exerted by said bar in tending to assume a position from which it was sprung.

3. A rail stay, comprising a transversely disposed bar provided at one end with means for engaging the rail base flange and at the other end with a rail base edge engaging shoulder and means, in spaced relation to said bar, adapted to engage the rail base and a cross tie and exert pressure upon said bar to retain said shoulder in engagement with the rail base edge.

4. An anticreeper, comprising a plate 75 extending beneath the rail base having upwardly extending end portions provided with shoulders engaging opposite side edges of the rail base, said plate having an integral arm for supporting one end upon the 80 rail base, means acting upon the other end of said plate and the rail base for exerting a vertical pressure upon said plate and means engaging a cross tie for holding one end of said plate in spaced relation to said 85 cross tie.

5. A rail anchor, comprising a cross bar having flat upwardly extending end portions provided with faces engaging vertical edges of the rail base at opposite sides of the 90 rail, an arm engaging the upper surface of the rail base at one side of the rail and a tie-engaging portion yieldably connected to said cross bar engaging the upper surface of the rail between the tie and said cross bar 95 and pressing one end of said cross bar upwardly against the rail bottom and holding the other end of said cross bar in spaced relation to said tie.

6. The combination with a cross tie and 100 a railroad rail having a base flange, of an anticreeper, comprising a plate extending beneath the base flange having upwardly extending end portions provided with inner edges engaging side edges of the base flange, 105 said plate being provided with means for supporting it on the base flange, and means, acting upon one end of said plate, the base flange and the cross tie for exerting a vertical pressure upon said plate and maintaining 110 the other end of said plate in spaced relation to the cross tie.

7. A device for preventing the creeping of rails, comprising a plate having one edge formed with a jaw to engage the rail base at 115 one side of the rail and a shoulder to engage the edge of the rail base at the other side of the rail and a portion of the other edge overturned to form a tie-engaging portion provided with an arm adapted to engage the upper surface of the rail base between the tie and said shoulder.

8. The combination, with a cross tie and a railroad rail having a base flange, of a rail anchor, comprising a cross bar having flat 125 upwardly extending end portions provided with shoulders engaging opposite side edges of the base flange and an arm engaging the upper surface of the rail base flange at one side of the rail and a tie engaging element 130

yieldably connected to said cross bar engaging the upper surface of the rail between the tie and said cross bar and pressing one end of said cross bar upwardly against the 5 rail bottom and maintaining the other end of said bar in spaced relation to the crosstie.

9. A one piece rail anchor, comprising a plate formed to engage the edge and upper surface of the rail base, at one side of the 10 rail, the tie and the upper surface of the rail base, at the other side of the rail, and provided with a rail edge engaging portion adapted automatically to engage the edge of the rail base when said anchor is forced into 15 position and to lock said anchor upon the rail base.

10. An anticreeper formed of a plate having a portion arranged to engage the edge and upper surface of the rail base at one 20 side of the rail, a portion adapted to engage a cross tie and the upper surface of the rail base and, in spaced relation to said tie-engaging portion, a portion adapted to engage the rail base edge at the other side of the rail, the whole being so arranged that, when said base edge and upper surface engaging portion is engaging the rail base at 25 one side of the rail and said tie and base engaging portion is engaging the rail base at 30 the other side of the rail, by angular movement of said anticreeper upon the rail base in one direction, said rail base edge engaging portion may be brought into such engagement with the rail base edge as to 35 prevent reverse angular movement of said cross bar upon the rail base.

11. A one piece rail anchor, comprising a plate having base edge gripping portions formed upon its ends, an arm adapted to 40 engage the upper surface of the rail base at one side of the rail and a tie-engaging portion, in spaced relation to said rail edge engaging portions, provided with means for engaging the upper surface of the rail base 45 at the other side of the rail, the whole adapted to be placed in position upon the rail by horizontal angular movement in relation to the rail and to be automatically locked upon the rail by the engagement of the base edge 50 gripping portions with opposite edges of the rail base.

12. A one piece anticreeper cut from a metal plate formed with a transversely disposed body portion having an arm and a 55 face adapted to engage the upper surface and edge of the rail base at one side of the rail and a rail edge engaging face adapted to engage the rail edge at the other side of the rail and a tie-abutting portion formed 60 by bending one edge of said plate forwardly and flanging it upwardly, said tie-abutting portion being provided with an arm adapted to engage the upper edge of the rail base at one side of the rail.

13. A rail anchor, comprising a metal 65 plate bent to trough shape one of the sides arranged to form a tie-engaging element having an arm adapted to engage the upper surface of the rail base at one side of the rail and the other side recessed to receive the 70 rail base and grip the opposite edges thereof and provided with an arm adapted to engage the upper surface of the rail base at the side of the rail opposite to the arm upon said tie-engaging portion. 75

14. An anticreeper, comprising a trough-shaped plate a portion of one side of which is cut away leaving a tie abutment formed with an arm adapted to engage the upper surface of the rail base and a portion of the other side of which is cut away to form an arm adapted to engage the upper surface of the rail base at the side of the rail opposite to said tie abutment and two rail base edge engaging faces adapted to grip 80 opposite edges of the rail base. 85

15. A one piece device for preventing the creeping of rails blanked from a metal plate to form a transverse body having at one end 90 a jaw adapted to engage the edge and upper surface of the rail base and, at the other end, a trough shaped portion one side of which engages the tie and the upper surface of the rail base and the other side of which forms part of said transverse body 95 and has a shoulder adapted to engage the rail base edge opposite to said jaw.

16. A rail anchor, in one piece, blanked from a metal plate formed with a transverse body portion having at one end a jaw 100 adapted to engage the edge and upper surface of the rail base and, at the other end, a trough shaped portion one side of which engages the tie and the upper surface of the rail base and the other side of which forms 105 part of said transverse body portion and has a face adapted to engage the rail base edge opposite to said jaw, all so proportioned and arranged that, when said jaw is in engagement with the rail at one side and the tie-engaging portion is in engagement with the rail base at the other side of the rail, by angular movement of said anchor upon the rail base in one direction, said rail base edge 110 engaging face may be brought into such engagement with the rail base edge as to prevent reverse angular movement of said cross bar upon the rail base. 115

17. A rail anchor, comprising a plate having a portion of one edge recessed and bent to form a tie-abutting portion provided with an inwardly extending arm adapted to engage the upper surface of the rail base back of said tie-abutting portion and the other edge to form a shoulder adapted to engage the rail base flange back of said tie-abutting portion and with rail base engaging means 120 at the free end of said plate. 125

18. An anticreeper, comprising a transverse plate having at one end a tie-engaging portion yieldably connected to said plate, an arm connected to said tie-engaging portion and engaging the upper surface of the rail base behind said tie-engaging portion and a shoulder engaging the vertical edge of the rail base at one side of the rail behind said tie-engaging portion and, at the other end, a jaw engaging the rail base at the other side of the rail.

19. A one piece rail anchor, comprising a plate flanged to engage a cross tie at one side of the rail and formed with arms engaging the rail base at opposite sides of the rail and a shoulder opposite one of said arms adapted automatically to engage the edge of the rail base flange when said an-

chor is forced into position to lock said anchor in place upon the rail base.

20. A device for preventing the creeping of rails, comprising a transverse plate recessed at one edge to receive the rail base and grip the opposite edges thereof and flanged at the other end on the other edge to form a tie-engaging portion, said plate having portions thereof bent toward one another to form arms adapted to engage the upper surface of the rail base at opposite sides of the rail forward of said transverse plate and in rear of the tie-engaging portion thereof.

H. G. GILLMOR.
